Primary Examiner — Mehri F Bajoul(57) **CLAIM**

The ornamental design for a foldable steering wheel stand, as shown and described.

DESCRIPTION

FIG. 1 is a front and top perspective view of a foldable steering wheel stand, showing my new design;
FIG. 2 is a rear and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is another perspective view thereof, shown in an alternative position; and,
FIG. 10 is an enlarged perspective view of detail “10” identified in FIG. 2.

The dashed lines in the figures illustrate portions of the foldable steering wheel stand that form no part of the claimed design. The dash dot dash lines in FIGS. 2 and 10 are for the purpose of illustrating the enlarged view indicators and form no part of the claimed design.

1 Claim, 10 Drawing Sheets(56)
